UNITED STATES PATENT OFFICE.

WILLIAM R. BECKMANN, OF ST. LOUIS, MISSOURI.

WIRE-ROPE MACHINE.

SPECIFICATION forming part of Letters Patent No. 440,859, dated November 18, 1890.

Application filed February 25, 1890. Serial No. 341,711. (No model.)

To all whom it may concern:

Be it known that I, WILLIAM R. BECKMANN, of St. Louis, in the State of Missouri, have invented certain new and useful Improvements 5 in Wire-Rope Machines, of which the following is a full, clear, and exact description, reference being had to the accompanying drawings, forming a part hereof.

My invention relates to an improvement in 10 machines for twisting wires, cordage, or the like; and it consists in the novel construction, combination, and arrangement of devices hereinafter described, and pointed out in the claims.

15 In the drawings, Figure 1 is a front elevation of part of a rope-making machine having my improvements applied thereto, portions of the flier-carrier being broken away. Fig. 2 is a central vertical cross-section thereof, 20 of, parts being shown in elevation. Fig. 3 is a plan view of a portion of the improved flier-carrier and other parts. Figs. 4, 5, and 25 6 are detail views of a roller and its mountings used in making up the invention. Fig. 7 is a detail view in perspective of a hardened-metal bearing-plate, also made use of in the invention.

1 indicates the flier, of which a suitable number are provided, with journals 2 at each 30 end and mounted in bearings in two circular plates 4, carried by shaft 5. A spool 6, having a bore therethrough, is mounted on pin 7 in the flier, so as to reel off the wire or cord as it is made use of.

35 Heretofore the fliers have been made of ordinary soft iron or steel with holes for the pin 7 drilled directly through their side bars, and as no provision has been made for wear caused by the heads of the spools abrading 40 said side bars as the nut on one end of pin 7 was tightened up from time to time the consequence has been that the spool would soon wear into said side bars and in taking up the wear by drawing in the side bars the journals 45 of the flier have been thrown so badly out of alignment as to render the flier worthless and necessitate its replacement by a new one. For preventing such wear of the side bars of the flier I have conceived the idea of placing 50 a hardened-steel plate 8, having a central aperture 9 for passage of the spool-pin 7 and two threaded holes 10 on opposite sides of

said central aperture, which holes 10 are to be engaged by screws 11, passing through the side bars of the flier from the outside, the 55 plate being placed upon the inside of said flier with its central aperture in line with the pin-passages thereof. In some cases I may dispense with these ordinary pin-passages in the frame-work of the flier, mounting the 60 spool solely in the central apertures of the hardened plates.

Heretofore flier-carriers have consisted of a main shaft, such as 5, which carried two circular plates or rings, such as 4, in which 65 the fliers have been journaled in ordinary holes, which construction has necessitated the bodily removal and consequent loosening upon the shaft of at least one of such plates should such an accident happen to a single 70 flier as would necessitate its removal for repair.

To permit the removal of any one of a series of fliers from a carrier without disturbing any of the others of the series is the object 75 of the construction now to be described.

The plates 4 are usually made with radial openings 40 between spokes, and it is through these openings that the flier may be removed by the use of my invention. Bearing-boxes 25 are preferably cast integral with the plates 80 at intervals around the inner periphery of the same at the usual places of location of the old bearing-apertures, and in these the journals 2 of the fliers are adapted to revolve. Removable caps 25^x, which are held in place 85 by bolts 26 and nuts 27, permit the ready removal of any flier without disturbing any other of the series carried by the carrier.

31 is a shoulder (or it may be a collar) on the lower journal of each of the fliers to support 90 the weight of the same.

Heretofore, also, much destructive wear has been occasioned in these machines by the cutting out of the bore of the hollow journal of the fliers by the abrasion of wire as it is 95 reeled off the spools, also entailing the loss of the flier on this account alone.

12 is the wire passing through bore 13, and as the pressure has always been applied in the same direction and at the same point only 100 a short period of operation has been necessary to accomplish the cutting out of the bore to such a degree as to render the flier useless.

14 is a peripherally-grooved roller jour-

naled in a bracket 15 at the inner terminal of the bore 13, so as to take the wire as it is reeled off the flier-spool and guide it centrally into and through said bore without contact with the latter. Said bracket 15 is provided with a flange 16, through which are passed screws 17, and by means of which it is secured to one end of the flier, so as to project the roller into the path of the outgoing wire, 10 said roller being thus located within the flier between the spool carried thereby and the hollow journal thereof. 18 is a similar roller journaled in an adjustable bracket-piece 19 at the outer terminal of the bore 13, which 15 takes the pressure of the wire after it issues from said bore.

20 is a bracket-piece, which is secured by a nut 21 to the upper one of the plates in which the hollow journals of the fliers are mounted, 20 and its outer end is perforated and provided with a set-screw 23, the shank of the adjustable piece 19 being adjustably located and held in the perforation in said piece 20. It is evident, however that I may make use of other 25 forms of brackets in which to mount the above-described rollers, the only essential thing being their point of location with respect to the bore of the hollow journals of the fliers, substantially as I have pointed out 30 above, and for the purposes mentioned there. 30 is a hole in the bracket 15 for passage of the wire.

The operation is as follows: The wire, in issuing from the fliers, instead of abrading 35 the bore thereof, will ride upon the rollers located in proximity thereto. When a flier is to be removed, this may readily be accomplished by removing the nuts 27, holding the caps of its boxes in place, all without dis- 40 turbing any other portion of the machine.

Having thus described my invention, what I claim is—

1. The combination, with the carrier-plates, of a revoluble flier-frame provided with journals having bearings in the said plates and 45 having a bore through one of the said journals, a roller mounted upon the flier-frame to take wire direct from the spool carried by the latter and guide it into said bore, a bracket supported in proximity to the bore of the flier-journal, and a roller mounted upon the said bracket to take the wire as it issues from the bore, substantially as set forth.

2. The combination, with the supporting-shaft, of the plates 4, having therein the openings 40, adapted to permit the insertion and removal of a flier-frame, the said plates being formed with fixed half-bearings at the outer sides of such openings, the flier-frame having journals fitted to such half-bearings, and 60 the cap-pieces removably secured to said half-bearings, substantially as described.

3. The combination of a revoluble flier having a bore through one of its journals and adapted to receive a spool mounted in said flier, with its journal extending transversely to the line of the journals of the flier, a roller 14, mounted upon the flier to receive the wire direct from said spool and guide it into said bore without contact of said wire and the interior of the bore, the flier-carrier, a bracket 19, located on said flier-carrier in proximity to said bore, and a roller 18, mounted upon said bracket to take the wire as it issues from the bore, substantially as set forth.

In testimony whereof I affix my signature in presence of two witnesses.

WILLIAM R. BECKMANN.
